CLAIM

I claim the ornamental design for a bracelet, as shown and described.

DESCRIPTION

The claimed bracelet is intended to be worn as an accessory on the wrist or ankle of the user.

FIG. 1 is a top view of a first embodiment of the invention.

FIG. 2 is a left side view thereof.

FIG. 3 is a right side view thereof.

FIG. 4 is a front view thereof showing the location of an optional graphical imprint in dashed lines.

FIG. 5 is a rear view thereof.

FIG. 6 is a bottom view thereof.

FIG. 7 is a top view of a second embodiment of the invention.

FIG. 8 is a left side view thereof.

FIG. 9 is a right side view thereof.

FIG. 10 is a front view thereof showing the location of an optional graphical imprint in dashed lines.

FIG. 11 is a rear view thereof; and,

FIG. 12 is a bottom view thereof.

The bracelet is comprised of linked rubber bands.

The broken line showing of an imprint in FIGS. 4 and 10 is for illustrative purposes only and forms no part of the claimed design.
